UNITED STATES PATENT OFFICE

JAMES O. McMILLAN, OF WICHITA, KANSAS

UNLOADING DEVICE

Application filed May 15, 1929. Serial No. 363,214.

This invention relates to improvements in unloading devices for air or gas compressors, and more particularly to a novel unloading device arranged in the discharge pipe of the 5 compressor and controlled by pressure in the compressor cylinder for automatically unloading the discharge pipe between the compressor and check valve whenever the compressor comes to a stop. Such unloading device 10 vice facilitates the starting of the compressor against the load, thereby preventing the burning of the motor and transmission belt.

I have heretofore proposed a combination 15 check valve and unloader operating in the discharge pipe of the compressor, and actuated by the variations in the flow of air or gas through the device; and the primary object of the present invention is to provide an unloading device which is controlled by the 20 pressure in the compressor cylinder in starting, and by reduction of pressure in the unloading device back to the compressor cylinder after the compressor comes to a stop for unloading the discharge pipe.

Another important object of my invention 25 when used on small compressors, is to automatically drain the water and oil waste from the discharge line each time the compressor ceases its compressing operation. I am aware 30 that unloaders of the "bleeder" type are in general use, but such unloaders have given considerable trouble. The pressure switch bleeder valve is the type most generally in use on automatic motor driven compressor 35 units, and if the current fails or is switched off while the installation is in operation, the pressure switch remains closed, due to the fact that the pressure has not been built up to the cut-out point. Consequently, the 40 bleeder valve remains closed and the compressor is not unloaded. Subsequently, when the current is resumed, under such conditions, the installation will start against full tank pressure, which causes blowing of fuses, burning or jumping of belts, and sometimes a more 45 expensive occurrence, a burned out motor.

My invention eliminates the possibilities 50 of the above mentioned troubles, since the operation of the unloading device is independent of electrical means, and wholly dependent

on the movement of the compressor piston for opening and closing the unloader.

Another object is to furnish an unloading device designed to unload the discharge pipe so rapidly as to cause the ordinary check 55 valve between the receiver and the compressor to be instantaneously forced to its seat. Air check valves of the dash pot type, often fail to seat, due to sticking caused by oil waste or carbon deposits, which sticking results in 60 many other troubles.

Another object is to provide an automatic unloading device of durable and rugged construction, simple and cheap to manufacture, non-sticking, non-clogging, and positive in 65 action.

It may be stated further that most unloading devices in use today require adjusting means to have the device accord with the compressor for which it is used. As inexperienced operators do not know how to properly adjust such devices, or the adjusting means themselves become loose, and get out of order, this results in the device becoming clogged, therefore, it is a further object of this invention, 70 to provide an unloading valve which is fitted to the compressor and regulated automatically by the flow of air through the same, and which is not sensitive to clogging, due to the fact that it has a large bleeding port. 75

With the foregoing objects outlined and with other objects in view which will appear as the description proceeds, the invention consists in the novel features hereinafter described in detail, illustrated in the accompanying drawings, and more particularly pointed out in the appended claims. 85

Referring to the drawings,

Fig. 1 is a side elevation of a compressor and receiver, shown combined with one form 90 of my improved unloader.

Fig. 2 is an enlarged vertical sectional view, partly in elevation, of a portion of the unloading device.

Fig. 3 is a horizontal sectional view on the 95 line 3—3 of Fig. 2.

Fig. 4 is a similar view of a modification.

Fig. 5 is a longitudinal sectional view of a special check valve forming part of the apparatus shewn in Fig. 1. 100

In the drawings, 6 designates the cylinder of an air or gas compressor 7, which is driven by a motor 8, through the medium of a belt 9. The fluid compressed by the piston (not shown) of the compressor, is forced through the discharge pipe 10, into the receiver 11, and this discharge line is preferably provided with a manually controlled valve 12 and a check valve 13, the latter preventing any return of the compressed air or gas from the receiver to the compressor cylinder.

The parts 6 to 13 inclusive may be of conventional construction, and the present improvements includes a T 14 which may be connected as shown in Fig. 1, to an unloading chamber 15, the lower end of which is joined to my improved valve 16. This valve in turn has its lower end in communication with the upper end of the cylinder 6, by means of a narrow pipe 17.

As best shown in Figs. 2 and 3, the valve 16 is provided with an externally threaded axially disposed nipple 18 which may be screwed into the lower end of the unloading chamber 15, as shown in Figs. 1 and 2, or may be screwed directly into the T 14, as indicated at 19 in Fig. 4. A port 20 in the valve casing communicates with a chamber 21 of the casing, in which a valve 22 operates. While this valve may be of any suitable construction, it is preferably of the needle type, and its conical end 23 cooperates with an annular valve seat 24 provided at one end of the port 20. This valve has a disk 25 at one end which is pressed by a spring 26 against a flexible diaphragm 27 that is preferably clamped in position against one end of the casing by means of a threaded cap 28 which has an internally threaded port into which one end of the pipe 17 is screwed. The chamber 21 of the valve casing is in constant communication with the atmosphere by means of a pipe 29. As shown in Fig. 5, the pipe 17 is connected to the compressor cylinder by means of a special check valve 30.

This check valve is constructed to bleed in opposite directions. Its valve housing 37 has two valve seats 38 and 39 which cooperate with a ball 40. In this form of the invention, each valve seat has a bleed groove 41, 42. Consequently, with this form of check valve, while the compressor is forcing air through the pipe 17 into the chamber 36, the passage of air will be delayed due to the bleed groove 41. On the other hand, during unloading, the groove 42 will restrict the passage of air from the chamber 36, and somewhat retard the unloading.

As shown in Fig. 4, the pipe 17 is connected to the compressor cylinder by means of another form of check valve 30a which includes a tubular housing 31 that is internally threaded for connection with the pipe 17. This housing has an annular valve seat

32 that cooperates with a ball 33 which is forced towards the seat by a coiled spring 34. A bleed groove 35 extends along the bore of the housing from the valve seat toward the interior of the cylinder 6 for the purpose of delaying the return of the pressure fluid from the chamber 26 of the unloader valve to the compressor cylinder.

In operation, it will be understood that the compressor 6 will force the air or gas through the discharge pipe 10, into the air receiver 11. The pressure fluid will not alone be forced through the pipe 10, but it will immediately be built up in the chamber 36 to close the valve 22 to prevent any bleeding of the air to atmosphere through the pipe 29, while the compressor is in action. While the compressor is in action, especially with small compressors, water and waste oil will gather in the chamber 15, and my improved mechanism functions not alone to unload the compressor but to discharge such water and oil waste.

When the pressure in the receiver 11 reaches a predetermined degree, the motor 8 is automatically stopped by the usual cut-out means (not shown). Immediately when this occurs, the unloader comes into operation, and the check valve 13 is instantly forced to its seat to prevent any return of pressure fluid from the chamber 11 to the cylinder 6. As the compressor comes to a halt, the pressure in the cylinder 6 automatically lowers and consequently, the spring 26 forces the valve 22 away from its seat, so that pressure fluid in the conduit 10 and chamber 15 blows any water or oil waste out through the pipe 29 to atmosphere, and at the same time, it relieves the system at the entrance side of the check valve 13 of pressure fluid.

As shown in Fig. 5, the pressure fluid in passing from the chamber 36 to the cylinder 6, will pass through the bleed groove 42, and thus the releasing of the oil from the chamber 36 will be retarded to the desired degree.

On small compressor units, it is important to have what is termed an unloading chamber or cooler, and trap. This chamber traps much of the waste water and oil, it cushions the pulsations on the check valve 13, it cools the oil somewhat, and acts as an unloading chamber in that the compressor must turn over several times before building up much of a pressure. In draining oil from this chamber, it has always been necessary to do so by opening a cock by hand. In my improvements, this is done automatically each time the compressor comes to a stop. When the compressor comes to a stop, the valve 22 is unseated, and the fluid in the chamber 15 is forced out through the pipe 29. After the fluid has been expelled, the air in the discharge line will also be released, and the system unloaded, cleaned and ready to be started. When the unloading chamber 15 is used, the

valve 22 will close on the first two or three revolutions of the compressor, due to the fact that there is too much air space to be filled, and very little pressure being produced on the side of the diaphragm 27, next to the chamber 21.

5 My unloading valve indicated in its entirety by 16, made in one size, will operate successfully on several sizes of compressors, but after a certain size compressor, the unloading valve should be a size larger in proportion to the next sizes of compressors it is to be used on.

10 My unloader is simple, durable and of rugged construction. It is cheap to manufacture, dependable, positive in operation, comprises only a few moving parts, and can be easily assembled, even by an unskilled person. No adjustments are necessary with the same. There is no sticking, and no clogging. Furthermore, when it includes the chamber 15, the latter forms an automatic waste eliminator.

15 The terms and expressions employed hereinafter are used as terms of description, and not of limitation, and there is no intention in the use of such terms and expressions, of excluding any equivalents of the features shown and described, or portions thereof, but it is recognized that various structural modifications 20 are possible within the scope of the invention claimed.

25 What I claim and desire to secure by Letters Patent is:

25 1. In mechanism of the character described, in combination, a compressor having a discharge line, a conduit connecting said line to the cylinder of the compressor, and an unloading valve interposed in said conduit and functioning due to pressure change in the compressor cylinder to unload the compressor and discharge line.

30 2. In an apparatus of the character described, a compressor cylinder having a discharge line, a receiver connected to said line, a check valve interposed in said line for preventing pressure fluid from moving from the receiver to the cylinder, a conduit connecting the cylinder to said line and connected to the latter at a point between the check valve and the cylinder, and unloader valve means interposed in said conduit and functioning due to pressure change in the cylinder to release the pressure fluid from the discharge line and cylinder.

35 3. An apparatus as claimed in claim 2, in which said conduit includes an unloader chamber functioning to gather waste water and oil from the discharge line, the valve means being so arranged relatively to the unloader chamber as to discharge any water and oil waste from the unloader chamber when the unloader valve means opens.

40 4. An apparatus as claimed in claim 2, including a check valve arranged in said con-

duit between the unloader valve means and the cylinder.

5 5. An apparatus as claimed in claim 2, including a check valve interposed in said conduit between the unloader valve means and the cylinder, and functioning to allow the gradual flow of pressure fluid from the valve means toward the cylinder.

10 6. An apparatus as claimed in claim 2, including a check valve interposed in said conduit between the unloader valve means and the cylinder, and functioning to restrict the flow of pressure fluid from the valve means toward the cylinder, said last mentioned check valve comprising a notched seat 75 and a valve member cooperating with said seat.

15 7. An apparatus as claimed in claim 2, including a check valve arranged in said conduit between the unloader valve means and the cylinder, said last mentioned check valve including a housing provided with opposed 80 seats, and a valve member interposed in the housing and cooperating with both of said seats.

20 8. An apparatus as claimed in claim 2, including a check valve arranged in said conduit between the unloader valve means and the cylinder, said last mentioned check valve including a housing provided with opposed 85 seats, and a valve member interposed in the housing and cooperating with both of said seats, each of said seats being notched to allow the flow of pressure fluid to pass the valve member when the valve member is seated.

25 9. An apparatus as claimed in claim 2, in which said unloader valve means includes a valve seat, a valve member cooperating with said seat, and a diaphragm cooperating with the valve member for forcing the same 90 against its seat.

30 10. In an apparatus of the character described, an unloader valve housing, a diaphragm arranged in the housing and dividing the interior of the same into first and second chambers, a port to place the first chamber in communication with a compressor discharge line, a valve seat for said port, a valve member cooperating with said seat and adapted to be forced against the latter by the diaphragm under fluid pressure created in the second chamber, and a second port communicating with the first chamber and placing said first chamber in communication with the atmosphere.

35 11. In an apparatus of the character described, an unloader valve housing including a body having a removable cap, a flexible diaphragm arranged in said housing and clamped in position by the cap, said diaphragm dividing the interior of the body into first and second chambers, a port to admit pressure fluid to the first chamber and provided with a valve seat, a port to admit a pressure fluid to the second chamber, a valve 120

member movable with said diaphragm and arranged in the first chamber and cooperating with said seat, said valve member functioning to move toward the diaphragm when moving away from said seat and another port placing the first chamber in communication with the atmosphere.

- 5 12. In an apparatus of the character described, a compressor cylinder, a pressure fluid receiver, a discharge pipe connecting the cylinder to the receiver, a check valve interposed in said pipe for preventing the flow of pressure fluid from the receiver to the cylinder, an unloader chamber connected to the 10 discharge pipe at a point between the check valve and the cylinder and arranged to receive any liquid draining from the discharge pipe, an unloader valve connected to the lower end of the unloader chamber, and functioning to discharge air and gas from the unloader chamber, and a conduit placing said last mentioned valve in communication with the cylinder, whereby pressure created in the cylinder is used to close said unloader valve.
- 15 13. A compressor unloader comprising a valve casing to be connected to the discharge of a compressor between the compressor and check valve, a diaphragm in the casing, a cap clamping the diaphragm to the casing and forming with the latter upper and lower 20 chambers, a valve member in the upper chamber to open and close a port communicating the upper chamber with that of the compressor discharge, said casing having a second port communicating the upper chamber with the atmosphere, a pipe communicating the lower chamber with the compressor cylinder, a check valve in said pipe, means within the said check valve for automatically delaying the time for the compressor to take 25 the full load by permitting the air from the compressor to escape to the atmosphere through the unloading valve until sufficient speed has been attained to take the full load, whenever the compressor comes to a stop, 30 means being provided in the check valve connected to the compressor cylinder for releasing pressure on the diaphragm of unloader to open a port communicating the compressor discharge between the compressor and the 35 discharge check valve to atmosphere as the compressor comes to a stop, and means for releasing an accumulation of waste oil and water, a quick release of air from the discharge line also forcing the discharge check valve to seat.

JAMES O. McMILLAN.
